DESIGN FOR A CAMERA CASING

Walter D. Teague, New York, N. Y., assignor to Eastman Kodak Company, Rochester, N. Y., a corporation of New Jersey

Application November 21, 1936, Serial No. 66,058

Term of patent 14 years

To all whom it may concern:

Be it known that I, Walter D. Teague, a citizen of the United States, residing at New York city, in the county of New York and State of New York, have invented a new, original, and ornamental Design for a Camera Casing, of which the following is a specification, reference being had to the accompanying drawing forming a part thereof:

In the drawing:

Fig. 1 is a perspective view of a camera casing showing my new design.

Fig. 2 is a top plan view of the camera casing shown in Fig. 1.

Fig. 3 is a front elevation of the camera casing shown in Fig. 1.

I claim:

The ornamental design for a camera casing, as shown.

WALTER D. TEAGUE.
